UNITED STATES PATENT OFFICE.

LEO E. GRONKOWSKI, OF EVERSON, PENNSYLVANIA.

WRENCH.

1,047,046.

Specification of Letters Patent. Patented Dec. 10, 1912.

Application filed June 28, 1911. Serial No. 635,736.

To all whom it may concern:

Be it known that I, LEO E. GRONKOWSKI, a citizen of the United States, residing at Everson, in the county of Fayette and State 5 of Pennsylvania, have invented new and useful Improvements in Wrenches, of which the following is a specification.

This invention relates to improvements in wrenches, and the primary object of the invention is to provide a wrench having one of its ends formed with a head block or frame which is so arranged as to support and guide a pair of movable jaws, said jaws having actuating mechanism whereby each 15 of the said jaws are simultaneously drawn toward each other or separated as desired.

With the above objects in view, and others which will appear as the nature of the invention progresses, the improvement resides 20 in the novel construction and arrangement of parts hereinafter fully described and claimed.

In the drawings, accompanying this specification, there has been illustrated a simple 25 and preferred embodiment of the improvement, and in which drawings,—

Figure 1 is a front elevation of a wrench constructed in accordance with the present invention. Fig. 2 is a vertical sectional view upon the line 2—2 of Fig. 1. Fig. 3 is a horizontal sectional view taken approximately central of the frame of the wrench. Fig. 4 is a front elevation of another form 35 of the wrench. Fig. 5 is a similar view of a still further modification. Fig. 6 is an elevation of another modification. Fig. 7 is an elevation of a still further modified form of the device. Fig. 8 is a side elevation of the wrench.

40 The improved wrench comprises a rod 1 having its upper extremity formed with an off-set portion 2, the said rod 1 and off-set forming the handle for the wrench. This handle may be either integrally connected 45 with a head or frame or may be removably secured thereto as desired. The frame 3 is of a substantially rectangular formation, the same comprising side members 4 which, as illustrated in the side elevation, prefer- 50 ably have their opposite ends bifurcated, and arranged within the said bifurcations are the longitudinal members 5 and 6 of the frame. The lower member 5 preferably 55 comprises a single strip of some suitable flattened metal, while the upper member 6

is centrally formed with a longitudinally extending tongue 7, and spaced away from the said tongue adjacent the opposite faces thereof, the member 6 is formed with downwardly extending longitudinally projecting flanges 8. The upper longitudinal member 6 is preferably formed with an upstanding yoke 9, said yoke having a suitable opening which alines with a similar opening in the member 6. Both of these openings are angular and are adapted to receive the angular extension of the rod 1. As heretofore stated, the rod may be integrally formed with the frame if desired or may be of a construction as above described.

The side members 4 terminate approximately central of the lower longitudinal connecting member 5, as clearly illustrated in the figures of the drawings, and the said side members are each provided with suitable registering depressions which are adapted to receive the ends of a screw 10. This screw 10 is provided with a milled head 11, the same being of a circular formation, and, as illustrated in Figs. 1, 4, 5 and 6 of the drawings, is arranged centrally of the screw 10. The portions of the screw extending from the opposite sides of the milled head 11 have their teeth arranged at an opposite pitch, the purpose of which will presently 85 be set forth.

The numerals 12 and 13 designate the sliding jaws for the device. These jaws are formed with threaded openings which are adapted to be engaged by the oppositely pitched threads of the screw 10, and whereby upon the rotation of the said screw, the jaws will be caused to travel simultaneously either toward or away from each other.

In Figs. 1 to 3 of the drawings, the jaws 95 12 and 13 are formed with lower openings 16 and 17, of a size and shape corresponding to the cross sectional form of the lower longitudinal member 5 of the frame. The upper extremities of the jaws are bifurcated 100 as at 18 so as to engage the opposite faces of the tongue 7, while the outer faces of the upper portion of the jaws are reduced so as to engage within the grooves formed between the tongue 7 and the flanges 8. By 105 this arrangement it will be noted that the jaws are effectively guided in their movement when the screw is rotated. The lower extremity of the jaws 12 and 13 are enlarged, the said enlarged portions provid- 110

ing shoulders which, when the jaws are in their full spread position, contact with the extremities of the side members 4.

In Fig. 4 the frame is substantially similar to that heretofore described, excepting that the side members 4' of the frame are arranged flush with the lower longitudinal member 5' thereof. The jaws 12' and 13' have their enlarged portions arranged below the lower edge of the member 5'. The jaws are of course provided with suitable openings whereby they are positioned upon the said member 5' of the frame, and the upper extremity of the jaws is bifurcated to engage with the tongue 7 of the frame 7'. By this arrangement it will be noted that the shoulders formed by the enlarged portions of the jaws 12' and 13' at all times contact with the under face of the member 5' of the frame, so that the strain upon the screw 10' as well as the threaded openings of the jaws is effectively relieved.

In Fig. 5 the device is substantially similar to that described in connection with Fig. 1, except that the bifurcated extremities of the jaws 12^a and 13^a are not formed with the reduced extensions which engage with the pocket formed between the tongue and the flanges of the upper member of the frame.

In this figure the flanges are also disposed of.

In Fig. 6 the device is also similar to that set forth in connection with Fig. 1, the difference in this case being that the inner faces of the jaws are formed with cut away portions 19, the said cut away portions being arranged adjacent the milled head of the screw, and the said cut away portions forming pockets whereby the said jaws may be brought tightly into engagement with each other.

In Fig. 7 the frame 20 is provided with a transverse bar 21, the same being connected to the side members of the said frame and arranged a distance below the top connecting member thereof. The lower connecting member 22 is arranged in a parallel plane with the side members of the frame, and the enlarged portions of the jaws underlie the

said connecting member 22. In this instance one of the side members is formed with a depression 22' within which is partially arranged the milled head 23 of the oppositely pitched screw 24. The jaw adjacent the milled head 23 is also preferably recessed as at 25. The jaws 26 and 27 are provided with the openings whereby they engage the bar 21 and the lower connecting member 22 of the frame, and are, of course, provided with the oppositely pitched threaded openings for the reception of the screw 24. Both the heads of the jaws 26 and 27 as well as the upper ends thereof lie directly beneath the longitudinal bars of the frame, so that when the said jaws are engaged with a nut, bolt or the like, the pressure upon the screw is effectively relieved.

From the above description, taken in connection with the accompanying drawings, the simplicity of the device, as well as the advantages thereof will, it is thought, be perfectly apparent to those skilled in the art to which such inventions appertain, without further detailed description, it being understood that changes as to size, shape, proportion, material, etc., which fall within the scope of the appended claim may be resorted to, if desired.

Having thus described the invention, what I claim is:—

A wrench comprising a substantially rectangular frame, a pair of jaw members slidably mounted within said frame and adapted for engagement with each other, adjustable means for separating and closing said members, a shoulder formed on each jaw member, and a pair of shoulders formed on said frame and adapted for engagement with the shoulders on the jaw members upon separation thereof to reverse the same.

In testimony whereof I affix my signature in presence of two witnesses.

LEO E. GRONKOWSKI.
